UNITED STATES PATENT OFFICE.

ALEXANDER T. BROWN AND WILBERT L. SMITH, OF SYRACUSE, NEW YORK.

SAFETY-CATCH FOR GUN-LOCKS.

SPECIFICATION forming part of Letters Patent No. 350,109, dated October 5, 1886.

Application filed May 26, 1886. Serial No. 263,325. (No model.)

To all whom it may concern:

Be it known that we, ALEXANDER T. BROWN and WILBERT L. SMITH, both residing at Syracuse, in the county of Onondaga and State of New York, have invented certain new and useful Improvements in Safety-Catches for Gun-Locks, of which the following is a specification, reference being had therein to the accompanying drawings.

10 This invention relates especially to the safety device of the lock mechanism of concealed-hammer guns, especially breakdown guns, and is applicable to either single, double, or three barreled guns.

15 The invention consists in certain improvements in the construction of the safety locking mechanism connected with the gun-lock of a breakdown gun, substantially as hereinafter claimed.

20 Figure 1 is a side elevation of the breech portion of a double gun with lock and stock removed and parts of the tang broken out and with top lever at rest and triggers unlocked ready for firing; Fig. 2, a like view of same parts with top lever thrown around to operate the action and the triggers locked at "safety;" Fig. 3, a like view of same parts with triggers set to operate independently in firing; Fig. 4, a top plan of part of breech-block, tang, top 25 lever, and indicator; Fig. 5, a bottom plan view of parts shown in Fig. 4; Fig. 6, a vertical section on line X X, Fig. 2.

A indicates the breech-piece or recoil-shield attached to the frame of the gun. The forward frame, 1, is recessed for the lock at 3. The tang 2 extends backward from the breech-piece as usual, and carries the top lever, 4, connected to the action-post 5. The trigger-plate 6 is held by the main screw 7, and bears the trigger 8, all these parts being of usual construction, with exceptions hereinafter noted.

Near the top of action-post 5 there is a shoulder or arm, 9, having a face which bears against the slide-bar 26, which bar extends backward 35 under the tang and parallel therewith. In the under part of the tang are two recesses, 10 and 11. Back of these recesses there is a slot, 12, and notches 13 are made in the lower face of the tang still in rear of this slot. A sliding plate, 15, on top of the tang has a stud, 16, extending through the slot 12. This stud bears

a coiled spring, 17, held in place by a pin passing through the stud. The stud 16 passes loosely through a hole in sliding safety-bar 20 under the tang, and this bar is held up by the 55 spring 17, the rear end of the bar being turned up at 25, and forming a tooth or pawl, which engages the notches or rack 13 in the tang.

The triggers 8 have each a slot, 14, cut in or through them, and a rod, 28, has pins 29, which 60 enter said slots. The upper end of rod 28 enters a mortise, 21, in the sliding bar 20.

The safety-bar 20 is guided so as to move longitudinally of the tang by pin 23 entering slot 22 in said bar, and its front end, when in 65 its forward position, is in the line of movement of sliding bar 26. The front end of the safety-bar 20 and the rear end of slide-bar 26 may be turned out of the line of prolongation of their respective bodies, so as to be in line for engagement. (See Figs. 1 and 5.)

The piece 15 has a knob, 19, and an open slot, 18, above the tang. (See Fig. 4.) The tang bears the word "safe," or some other indicating device, which shows through the slot 75 18 when the piece 15 is in its intermediate position, but is covered when the slide is pressed either to front or rear.

As shown in Fig. 1, the triggers are in unlocked position. A pull on the trigger raises 80 bar 28, so that its upper end enters recess 10 in the tang. The movement of lever 4 in unlocking the breech causes shoulder 9 on the action-post 5 to press back the slide-bar 26, and this in turn presses back the safety-bar 20 85 and carries the top of bar 28 into position between the recesses 10 and 11 in the tang, as in Fig. 2, so that the triggers cannot be raised by pulling. The indicator now shows the word "safe" through slot 18. This position of the 90 safety-bar 20 is as far to the rear as the movement of slide 26 extends, and the engagement of tooth 25 with rack 13 holds the safety-bar in this position.

When it is desired to throw the safety apparatus out of engagement with and free it from the control of the lever apparatus, the bar 20 is drawn (by button 19) still farther back, and the top of rod 28 is then under recess 11. The trigger may then be pulled without hindrance from said rod, and the safety-slide will be held by the tooth 25 engaging the 95 100

rack in the tang. Thus the safety-catch may be thrown into or out of engagement with the barrel-locking catch or lever, and may be operated either by said lever or by hand, or may 5 be left (in rearmost position) entirely inoperative.

The lock bar or rod 28 may be slotted to straddle the triggers, if desired.

We are aware that operating connections 10 from the breech-locking mechanism to the safety-catch of a breakdown gun are not broadly new; also, that a lever, connected with a trigger-locking device arranged to conceal an index on the frame has before been de- 15 scribed.

We claim—

1. The combination of the tang having two recesses therein, a safety sliding bar beneath said tang, a locking-bar extending up from the 20 trigger through said slide-bar into position to be shifted into line with either recess in the tang, and a slide-bar extending from the breech-operating mechanism into position to shift the locking position from beneath one of the tang recesses, but not from the other, substantially as described.

2. The combination, in a breakdown gun, 25 of the trigger-locking mechanism, the connection from the breech-locking lever in line therewith, but not attached thereto, and a slide on

the frame controlling the trigger-locking mechanism, said slide having a locked position to the rear of the position where it is engaged by the breech-locking mechanism, whereby the trigger-locking mechanism may be controlled or thrown out of the control of the breech-locking mechanism, substantially as described. 35

3. The combination, in a gun-lock, of a trigger-locking rod extending upward from the lock mechanism and having its upper end just 40 beneath the tang, a slide beneath the tang embracing the top of said rod, a slide or button on top of the tang connected to said inner slide and having a slot therein, and the tang having two recesses and an abutment on its lower face 45 in line with the different positions of the locking-rod, and having an index on its upper surface which is visible through the perforation in the sliding button in one position, but is covered in other positions of said slide, substantially as described.

In testimony whereof we affix our signatures in presence of two witnesses.

ALEXANDER T. BROWN.
WILBERT L. SMITH.
